INTEGRATING TIMER

Nils T. Almquist, New Britain, Conn., assignor to Raymond Engineering Laboratory, Inc., Middletown, Conn., a corporation of Connecticut

Application September 6, 1955, Serial No. 532,385

6 Claims. (Cl. 161—15)

This invention relates to a timing mechanism and more particularly to an integrating timing mechanism which is responsive to changes in acceleration or deceleration of the timer.

It is an object of this invention to provide a timing mechanism, the normal run down period of which may be varied over a wide range in response to changes in acceleration to which the timer is subjected.

It is another object of this invention to provide an acceleration responsive timer which will be sensitive to components of acceleration or deceleration in one direction but relatively insensitive to components of acceleration or deceleration in a transverse direction.

It is a further object of this invention to provide a timer of the type described which is compact and light weight in design to permit efficient use of limited space and which is simple in construction and operation utilizing a minimum of parts and providing trouble free service.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the drawings:

Fig. 1 is a plan view of an integrating timer constructed in accordance with this invention;

Fig. 2 is a side view of the timer of Fig. 1 with a portion of the timer housing cut away; and

Fig. 3 is a cross sectional end view of the acceleration responsive portion of the timer of Fig. 1.

Referring to the drawings, the acceleration responsive timer is comprised of a rectangular frame 10 on one end of which is mounted in depending position by means of screws 11 a housing 12 containing a clockwork mechanism 14. The clock mechanism, all the elements of which, for simplicity, are not shown, is conventionally comprised of an escapement 17 engaged by a verge 15, the rate of oscillating motion of which is determined by an elongated leaf type hairspring 16 operatively connected to the shaft of the verge. The hairspring 16 is so disposed that the majority of the oscillating portion of the spring extends outwardly and forwardly of the housing.

The frame 10 is provided with an aperture 20 which receives the downwardly struck end portion 25 or finger of a regulator lever 21. The end portion of the lever 21 is provided with a slot at 22 which slidably receives the hairspring 16, and thus provides a variable anchor for the end of the spring. The sides of the end portion 25 of the lever 21 are provided with notches at 23 and 24 which are engaged with the sides of the aperture 20 in order to guide the lever 21 as it is moved relative to the hairspring in a manner to be hereinafter described, to vary the effective length of the oscillating portion of the hairspring 16 and thus vary the period of oscillation of the verge 15. It can be seen from the drawings that

2

as the lever 21 is moved to the right or rear as viewed in Fig. 1, the run down period of the clock mechanism 14 will be decreased while the converse will be true if the lever is subsequently moved leftwardly or forwardly.

5 The relative location of the lever 21 with respect to the hairspring 16 is controlled by the weights 30 and 31 which are pivotally mounted on the side and end of the frame 10 opposite the clock mechanism 14 by means of pins 35 between the frame 10 and a cover plate 32 which is maintained from the frame 10 by the spacers 33 and 34. The spacers 33 and 34 also serve to limit the pivotal movement of the weights. The pins 35 to which the weights are secured are provided with shoulders 37 and 38 which engage the frame 10 and plate 32 to maintain 15 the weights spaced from the frame and plate to preclude frictional contact of the weights with the frame and cover plate. The inwardly extending weights 30 and 31 are symmetrical in shape and mounting having generally triangular planforms and with their centers of rotation on 20 the longitudinal centerline of the weights but offset outwardly from their center of gravity. For a purpose to be hereinafter explained it is preferable to mount the weights for counter rotation and in order to provide a compact design it is preferred that major portion of 25 one weight overlie the major portion of the other weight.

The weights are provided with recesses 39 to reduce the overall height of the assembly and the inwardly extending end portions of the weights are provided with an arcuate surface 41 to prevent interference between 30 the end of one weight and the shoulder 42 of the recess of the other weight.

An upwardly extending pin 45 is mounted in the weight 31 with its longitudinal centerline in registry with the longitudinal centerline of the weight and equidistant from 35 the pins 35. A roller 46 is rotatably mounted on the pin 45 and is received in and engaged by an elongated recess 47 in the underside of the weight 30. The center of the recess 47 is in registry with the center of the pin 45. In this manner unitary movement of the weights 40 30 and 31 in opposite directions is provided for a purpose hereinafter explained.

A lever 48 is pivotally mounted on the pin 45 intermediate the roller 46 and the weight 31. The lever 48 extends rearwardly and is provided at its rearward end with 45 a tongue 49 which is received in a slot at 50 in a U-shaped flat spring 51. The legs of the spring 51 are mounted by means such as the rivets 52 to the upwardly struck flanges 53 and 54 of the frame 10. The spring 51 co-operates with the lever 48 to provide a means for determining the 50 extent of pivotal movement of the weights 30 and 31 for a given acceleration. The lever 48 is preferably of light weight as compared to the weights 30, 31 to minimize the effect of side forces on the weights.

A downwardly extending pin 58 is mounted in the 55 weight 31 in alignment with the longitudinal centerline of the weight and adjacent the outer end of the weight opposite the pivot pin 35. Pivotally mounted on the pin 58 is the forward end of the regulator lever 21 hereinbefore described as cooperating with the weights 30, 31 60 to vary the effective period of oscillation of the hairspring 16. The lever 21 is also preferably of light weight as compared to the weights 30 and 31 to minimize any effects of side forces on the weights. The lever 21 is mounted adjacent the outer end of the weight in order 65 to obtain the maximum throw for any given amount of pivotal movement of the weight.

From the above it can be seen that as the timer is forwardly accelerated to the left as viewed in Fig. 1 the weights 30 and 31 will be pivoted clockwise and counter-clockwise respectively against the face of the spring 51 to move the regulator lever 21 relative to the hairspring 16.

It is believed the operation of the acceleration responsive timer will be apparent from the above description and following explanation. The timer is designed to be responsive to acceleration forces directed along the longitudinal centerline of the frame 10. Assuming the timer to be moving to the left as viewed in Fig. 1 at a calculated normal acceleration rate the spring 51 and weights 30 and 31 are so selected with respect to the length of the hairspring 16 that the regulation lever 21 will be positioned relative to the hairspring at a preselected point to the right of the position shown in Fig. 1 but somewhat to the left of the clock housing 12. If for any reason the rate of acceleration is increased or decreased the weights 30, 31 will cause the lever 21 to be moved to the right or left respectively to increase or decrease the period of the verge 15 and thus the speed of the clock mechanism 14. It has been found that with a timer constructed in accordance with this invention, variations of up to 30% may be obtained on the run down period of the timer.

The mounting of the weights 30 and 31 to provide counter-rotational movement results in the cancelling of the effect of any component of an accelerational force imposed on the timer except that component directed along the longitudinal centerline of the frame 10. It can be readily seen if a force normal to the path of movement is directed against the weight 30 to rotate the weight in a clockwise direction, this same force will also tend to rotate the weight 31 in the same direction. Inasmuch as the weights are interconnected for unitary counter-rotation this tendency of movement of the weights will be cancelled out.

The light weight of the levers 21 and 48 with respect to the weights assures that any forces on these levers will not significantly affect the run down period of the timer.

Thus it can be seen that there has been provided a timer having provisions whereby the period of run down of the timer is modified in response to changes in acceleration of the timer in one direction only.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. An integrating timer comprising an escapement having a hairspring and means responsive to acceleration of the timer for varying the effective length of the hairspring comprising a weight mounted for movement in one direction in response to acceleration of the timer, biasing means urging the weight in a direction opposite said one direction, and a linkage mounted at one end for movement with the weight in either direction of movement of the weight and slidably connected at the other end to the hairspring.

2. An integrating timer comprising an escapement having a hairspring, movable anchor means for one end of the hairspring, a pivoted weight mounted for pivotal

movement in one direction in response to acceleration, a spring biasing the weight in a direction opposite to said one direction, and a linkage mounted at one end for movement with the weight in either direction of pivotal movement of the weight and connected at the other end for movement to the movable anchor means.

3. An acceleration response integrating timer comprising an escapement with an oscillating verge, an oscillating hairspring operatively connected to said verge, a regulator arm slidably engaged with said hairspring and mounted for movement relative to said hairspring to vary the effective length of the oscillatable portion of said hairspring, a pair of interconnected symmetrical weights eccentrically mounted for counter-rotational movement in

15 response to accelerating biasing means to regulate the position of said weights in relation to the degree of acceleration imposed on said timer, and connecting means to move said regulator lever relative to said hairspring in response to movement of said weights.

20 4. An acceleration responsive integrating timer comprising a frame, a clockworks mounted on the frame, a hairspring forming a part of the clockworks having a free end portion extending linearly outwardly of the clock-

25 works, a pair of interconnected weights pivotally mounted on the frame for counter-rotational movement responsive to acceleration, a lever slidably mounted on the frame having one end connected to the weights and having its other end slidably embracing the free end portion of the hairspring, and means biasing the weights in one direction.

5. An acceleration responsive integrating timer comprising an elongated frame, a clockworks mounted on one end of the frame having a leaf type hairspring ex-

35 tends longitudinally of the frame, a pair of overlying symmetrical weights pivoted at the opposite end of the frame for pivoting movement responsive to acceleration longitudinally of the frame, a pin and slot connection between the weights, a U-shaped spring mounted intermediate the clockworks and pivoted weights, a linkage between the pin and the spring, and a link connected at one end to one of the weights remote from the pivot thereof and having its other end mounted for sliding movement longitudinally of the frame, said other end being slotted to slidably embrace the end of the hairspring.

40 6. An integrating timer comprising an escapement having a hairspring, a slide on one end of the hairspring for varying the effective length thereof, a pair of pivoted weights mounted for rotation in opposite directions in response to acceleration of the timer in a predetermined direction, a spring biasing the weights in a direction opposite said predetermined direction, a linkage mounted at one end for movement with said slide, and means connecting the other end of the linkage for movement with both of said weights.
